(57) **CLAIM**

The ornamental design for a camera, as shown and described.

DESCRIPTION

FIG. 1 is a perspective view of a camera showing our new design;

FIG. 2 is a right side elevational view showing the design for the camera of FIG. 1;

FIG. 3 is a left side elevational view showing the design for the camera of FIG. 1;

FIG. 4 is a front elevational view showing the design for the camera of FIG. 1;

FIG. 5 is a rear elevational view showing the design for the camera of FIG. 1;

FIG. 6 is a top plan view showing the design for the camera of FIG. 1; and,

FIG. 7 is a bottom plan view showing the design for the camera of FIG. 1.

The broken line shown in the drawings illustrate portions of the camera that form no part of the claimed design.
